United States Patent

Des. 235,593
Patented July 1, 1975

235,593

SIDE CHAIR

Maxwell E. Pearson, Zionville, Pa., assignor to Knoll International, Inc., New York, N.Y.

Original design application Sept. 16, 1968, Ser. No. 13,539,
now Patent No. 219,376. Divided and this application
June 17, 1970, Ser. No. 23,531

Term of patent 14 years

Int. Cl. D6—01

U.S. Cl. D6—30

Fig. 1.

Fig. 2.

FIG. 1 is a perspective view of an armless chair embodying the new design.

FIG. 2 is a rear view of the chair of FIG. 1.

The dominant features of the design are shown in full line in the figures.

This application is a division of my co-pending application Ser. No. D. 13,539, filed Sept. 16, 1968, for chair, now Pat. No. D. 219,376.

I claim:

The ornamental design for side chair, as shown.
